UNITED STATES PATENT OFFICE.

JACOB E. SMITH, OF HOMESTEAD, PENNSYLVANIA, ASSIGNOR, BY DIRECT AND MESNE ASSIGNMENTS, TO PENNSYLVANIA STEEL TIE COMPANY, OF ALLEGHENY COUNTY, PENNSYLVANIA, A CORPORATION OF PENNSYLVANIA.

RAILROAD-TIE.

No. 825,357.

Specification of Letters Patent.

Patented July 10, 1906.

Application filed February 14, 1905. Renewed November 17, 1905. Serial No. 287,846.

To all whom it may concern:

Be it known that I, JACOB E. SMITH, a citizen of the United States, residing at Homestead, in the county of Allegheny and State of Pennsylvania, have invented a Railroad-Tie, of which the following is a full and exact specification.

This invention relates to railroad-ties, and more especially to that class of such ties which are made entirely of metal.

It is well known that railroad-ties constructed of metal possess many advantages over the ordinary wooden ties, and therefore many attempts have been made to provide a metal tie that would meet all the requirements of a perfect tie without adding materially to the expense as compared with the wooden tie. So far as I am aware such attempts have been unsuccessful, inasmuch as they have failed to produce a light and cheap device that will properly grip the road-bed and give the required bearing-surface for the rails.

My invention therefore, contemplates the provision of a metal railroad-tie which is cheap and simple in construction, light in weight, and when in use will provide a firm grip or hold on the road-bed to prevent longitudinal or lateral displacement and also provide a wide bearing for properly supporting the rails.

In connection with my improved tie I employ attaching means for the rails especially adapted thereto.

My invention consists, primarily, of a metal railroad-tie made of an angle-beam, the ends of which beam are bent upon themselves to provide wider bearings for both the tie itself and the rails which are supported thereby.

My invention further consists in the particular formation of the metal tie and in the peculiar means for attaching the rails thereto, all as will be hereinafter fully described, and more specifically set forth in the appended claims.

In the accompanying drawings, which form a part of this specification, Figure 1 is a front elevation of a metal tie constructed in accordance with my invention, the rails being shown secured thereon. Fig. 2 is a plan view of Fig. 1, the rail at one end of the tie being removed to more clearly show the construction and arrangement of the rail-secur-

ing means. Fig. 3 is a detail end view of the tie, slightly enlarged, with the end of the tie broken away to show the rail-securing means. Fig. 4 is a detail perspective view of one of the rail-clamping members. Fig. 5 is a detail view of the washer which is interposed between the rail-clamping members. Fig. 6 is a plan view of a modification of the tie.

In Figs. 1 to 5, inclusive, of the drawings I have illustrated the preferred form of construction, in which the letter A designates the tie, and in this instance the said tie is formed from an angle-beam, preferably L-shaped in cross-section, such as commonly employed in metal construction work. A suitable length of such beam is employed, and the ends are bent or rolled to provide a loop, as a, at each end of the tie, and so that the lower flange a' will project outwardly with respect to the loop, as shown. By shaping the ordinary angle-beam in this manner I am enabled to produce a tie which in use will possess the required stability and all the other requisites of a practical tie, inasmuch as by turning the ends into the form of opposing loops with the base-flanges thereof extending outward the ends of the tie will have considerable bearing and holding capacity in the road-bed, and the upper edges of the loop portions being spaced apart will provide a wide bearing for the rails. Thus it is possible to produce a metal tie of light and simple construction, and consequently cheap, with the ends which in use receive the greatest strain properly reinforced and braced for all purposes.

As herein shown, the loops which are formed at the ends of the tie are open at their inner ends and present parallel vertical walls which are adapted to receive the rail-securing means hereinafter described, and in the application of the tie, the material forming the road-bed completely embeds the same, being tamped on both sides and in the opposite loops, the particular shape of the latter providing a firm hold and bearing to prevent either longitudinal or lateral movement of the tie. To further increase the holding capacity of the tie, I may and preferably do stamp from the base-flange a' of said tie a number of lugs or projections a², adapted to enter the ground or road-bed.

It is obvious that the shape of the tie when

constructed of angle-beam, as herein proposed, may be varied and still retain the feature of the looped ends, a modification being suggested in Fig. 6, wherein a beam A', having opposite base-flanges, is employed and the loops a^3 disposed at opposite sides instead of one side only, as in the form heretofore described. In this modification a portion of one of the base-flanges, as a^4 , is necessarily cut away to permit the loop to be formed with the vertical walls a^5 of said loop approximately close together, said walls being parallel to receive the rail-securing means.

In connection with the peculiar construction of tie hereinbefore described I provide particular means for attaching or securing the rails thereto. Such means comprise a pair of oppositely-disposed clamping members B B', the jaws b, which engage the rails, being enlarged laterally at the outer side to form shoulders b', which latter rest upon the upper edge of the tie when said clamping members are clamped on the rails. The lower or body portion b^2 of each clamping member is provided with bolt-holes b^4 and b^5 , the bolt-hole b^5 being slightly elongated for the purpose hereinafter explained. The bolt-holes in the companion clamping members are adapted to align with each other, respectively, and with corresponding bolt-holes a^6 and a^7 in the loop portion of the tie. Through the registering bolt-holes b^4 and a^6 passes an ordinary bolt C', and through the elongated bolt-holes b^5 and a^7 passes a wedge-shaped bolt C, the latter being employed to bind the clamping members on the rails and hold the latter rigidly in place. These bolts C and C' are each provided with the usual nut, as c.

The clamping members B when applied are located in the loop portion of the tie and are held against the vertical sides of the same with the shoulders b' resting on the tie by means of a washer, as C³, interposed therebetween, though obviously if the loop was narrower such washer would not be required. The jaws b of the clamping members are shaped to properly engage the base-flange and web of the usual type of railroad-rail S at opposite sides thereof, and in applying the bolts to connect the parts the wedge-bolt is driven in or drawn tightly by its nut, so as to rigidly clamp the rails, as before stated.

Where a guide-rail, as S', Fig. 6, is to be used in connection with the running-rail, a block, as D, is interposed between said rails, and in this instance one clamping member, as B³, is located on the outer side of the running-rail S, while a second clamping member, as B⁴, is located on the opposite or inner side of the guide-rail S'. The block D and clamping member B⁴ are preferably bifurcated, so as to straddle the vertical flange of the tie, and are held in place by the bolts d and b⁶, respectively. Between the rail and tie is placed a wear-plate a⁸, extending across the

loop and seated in recesses in the upper edges thereof.

The construction of tie and rail securing means hereinbefore described provides a firm support for the rails and effectually prevents spreading or shifting of the same, inasmuch as the retaining-jaws are strongly made and securely connected to the tie, while the tie itself has a firm bearing in the road-bed. It is also obvious that the tie being light in construction can be easily handled and requiring only a minimum amount of metal in its construction can be produced at small cost.

By forming the tie of an angle-beam with open-ended loops at its ends, as herein shown and particularly described, such form of loops not only serves to more effectually increase the holding capacity of the tie with relation to the road-bed, but also makes it convenient in manipulating the rail-securing means, as well as in filling around the tie after the latter has been properly set.

Having thus described my invention, what I claim as new, and desire to secure by Letters Patent, is—

1. A metal railroad-tie the ends of which are formed into loops having vertical parallel walls and lateral base-flanges.

2. A metal railroad-tie the ends of which are formed into loops open at their inner ends, said loops having vertical walls and lateral base-flanges.

3. A metal railroad-tie comprising a bar or beam L shape in cross-section and bent upon itself at its ends forming loops with vertical walls and lateral base-flanges.

4. A metal railroad-tie the same comprising a bar or beam L shape in cross-section and bent upon itself at its ends forming open-ended loops with vertical walls, the lateral flange of the bar forming the base-flange of the tie.

5. A metal railroad-tie, comprising an angle-bar providing vertical and lateral members and formed at its ends into loops with the lateral member or flange projecting outwardly with respect to said loops.

6. A metal railroad-tie the same comprising a bar or beam L shape in cross-section and provided on the lower lateral flange with lugs stamped therefrom, said bar or beam being bent upon itself at its ends forming open-ended loops with parallel vertical walls, the lateral flange of the bar or beam forming the base-flange of the tie.

7. In a metal railroad-tie, the combination, of a bar or beam the ends of which are bent in the form of loops having parallel vertical walls, clamping members located in the loops between said vertical walls and adapted to clamp the rails, and means for securing the clamping members in such engagement.

8. In a metal railroad-tie, the combination, of an angle bar or beam the ends of which are

formed into loops having parallel vertical walls, clamping members for the rails located in the loops between the parallel walls thereof and having shoulders resting thereon, and securing means for the clamping members.

9. In a railroad-tie, the combination, of an angle-beam the ends of which are formed into loops having parallel vertical walls, clamping members for the rails located in the loops between the vertical walls thereof and having shoulders adapted to rest thereon, a washer inserted between the clamping members, and securing-bolts passed through the clamping members, washer and tie, substantially as shown and described.

10. In a railroad-tie, the combination, of an angle-beam the ends of which are formed into loops having parallel vertical walls with bolt-holes therethrough, clamping members for the rails located in the loops between the vertical walls thereof, said clamping members having bolt-holes one of which is elongated, and securing-bolts one of which is wedge-shaped.

11. In a railroad-tie, the combination with the tie formed of an angle-beam with loops at the ends of the tie, said loops having vertical parallel walls, of clamping members located in the loops between the parallel walls thereof, said clamping members having lateral shoulders adapted to rest upon the upper edge of the tie, a washer interposed between

the clamping members, and securing-bolts passed through the tie and clamping members.

35

12. In a railroad-tie, the combination with the tie formed of an angle-beam bent to provide loops at the ends of the tie, such loop portions having bolt-holes, clamping members located in the loop portions of the tie and having bolt-holes corresponding with the aforesaid bolt-holes in the tie, shoulders projecting laterally from said clamping members and adapted to rest upon the upper edges of the loop portions of the tie, a washer interposed between the clamping members, and a plain bolt and a wedge-shaped bolt for securing the clamping members to the rails.

40

13. In a railroad-tie, the combination with the tie formed of an angle-beam bent to provide loops at the ends of the tie, said tie having bolt-holes, clamping members adapted to engage the rails, a block adapted to be interposed between the running-rail and guide-rail, and bolts for securing the clamping members and block in place.

45

In testimony whereof I have signed my name to this specification in the presence of two subscribing witnesses.

JACOB E. SMITH.
